UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND BRAKE.

Application filed September 8, 1921. Serial No. 499,212.

To all whom it may concern:

Be it known that I, JOHN F. O'CONNOR, a citizen of the United States, residing at Chicago, in the county of Cook and State 5 of Illinois, have invented a certain new and useful Improvement in Hand Brakes, of which the following is a full, clear, concise, and exact description, reference being had to the accompanying drawings, forming a part 10 of this specification.

This invention relates to improvements in hand brakes.

One object of the invention is to provide an efficient hand brake especially adapted 15 for railway cars and wherein is eliminated the usual pivoted spring-controlled locking dog.

Another object of the invention is to provide a brake of the character indicated 20 wherein is provided means for positively locking the brake against accidental release which means, when operated to release the brake, will positively insure the operating handle of the brake being rendered inoperative to the end that injury of the brakeman 25 will be avoided.

Other objects of the invention will more clearly appear from the description and claims hereinafter following.

30 In the drawing forming a part of this specification, Figure 1 is a vertical sectional view of a mechanism embodying my invention shown as applied to a railway car brake of the vertical staff type. Figs. 2 and 3 are 35 horizontal sectional views corresponding substantially to the section lines 2-2 and 3-3, respectively, of Fig. 1. Fig. 4 is a top plan view of a double-faced ratchet wheel employed in the construction. Fig. 40 5 is a bottom plan view of the holding ratchet wheel employed in my construction. Fig. 6 is a side elevational view of the member shown in Fig. 5 and Fig. 7 is a side elevational view of the ratchet wheel shown 45 in Fig. 4.

In said drawing, 10 denotes a portion of an end wall of a car and 11 the upper portion of a vertical brake staff, the latter having a squared top section as indicated at 12.

50 In carrying out my invention, I provide suitable brackets or supporting means adapted to be secured to the wall of the car, said means comprising an upper bracket 13 and a lower bracket 14. Said upper bracket 13 has a vertically extending web 15 by which

it is riveted to the wall and a horizontally extending web 16 having a depending annular flange 17. Said web 16 is also provided with an upwardly extended integral enlargement 18-19, the former being of 60 substantially square form providing an interior square socket 20. The upper part 19 may be rounded so as to provide a convenient hand grip for the brakeman.

The lower bracket 14 is provided with 65 stepped bearings 21 and 22 for the rounded part of the staff 11 and the cylindrical sleeve 23 of the double-faced ratchet wheel A which is rigidly applied to the squared section 12 of the staff. 70

The double-faced ratchet wheel A, rigidly secured to the staff as above described, is provided on the upper side thereof with a series of radially extending ratchet teeth 24-24 and on the under-side thereof with 75 a series of radially extending ratchet teeth 25-25. As will be understood by those skilled in the art and as shown best in Fig. 6, the teeth 24 and 25 face in opposite directions. 80

Journalized on the sleeve 23 is an annular carrier B, the same having an inner annular flange 26 directly engaging the sleeve 23 and an outer deeper annular flange 27 which, at its lower edge, is journalized on the upper 85 portion of the bracket 14. It will be noted that the two annular flanges 26 and 27 are concentrically arranged and leave an annular space therebetween in which is accommodated a spring 28 bearing at its upper end against the top wall 29 of the carrier B and at its lower end against the top face of the bracket 14. With this arrangement, it is evident that the carrier B is not only free to oscillate with respect to the staff 90 and ratchet wheel A carried thereby, but also to move up and down or axially of the staff. The carrier B, as best shown in Fig. 3, is provided with a pair of laterally extended flanges 30-30 between which is 95 pivotally mounted on the bolt 31, the gravity drop handle 32. 100

Vertically slidably mounted within the square socket 20 but non-rotatable with respect thereto, is the square hollow hub 33 105 of the locking ratchet wheel designated generally by the reference C and shown best in Figs. 5 and 6. The ratchet wheel C, on the bottom thereof, is provided with a series of radially extending ratchet teeth 124 adapted 110

to cooperate with the ratchet teeth 24 of the ratchet wheel A. Around its periphery, the ratchet wheel C is provided with a series of heavy steep-pitch threads 34, as best 5 shown in Fig. 6. The hub 33 of the ratchet wheel C is hollow, as heretofore described, and is adapted to accommodate therewithin a second spring 35 which bears at its upper end against a suitable shoulder provided by 10 the enlargement 19 and at its lower end against a suitable shoulder provided on the interior of the ratchet wheel C. With this construction it is evident that the ratchet wheel C will normally be held in its lowermost position but is, nevertheless, free to move upwardly against the action of the spring 35, both during the winding-up operation as the ratchet wheel A slips thereunder, and during the release, as hereinafter 15 described.

To release the mechanism, I employ an annular bushing 36 which is rotatably journaled within the flange 17 and on the top of the carrier B, as shown in Fig. 1. Said bushing 36 is formed on the inner side thereof with heavy steep pitch threads 37 cooperable with the threads 34. Said bushing 36 has a radially extended release handle 38.

The operation is as follows: To set the 30 brakes by rotating the staff 11 in a clockwise direction as viewed in Figs. 2 and 3, the brakeman elevates the handle 32 to the dotted line position shown in Fig. 1 and pulls the same toward him. The radially 35 extended teeth 125 on the top of the carrier B engage with the radial teeth 25 of the ratchet wheel A and thereby cause the staff to be rotated step by step in a clockwise direction. It is evident that as the handle 32 40 and carrier B are returned in a counter clockwise direction, that the teeth 125 will cause the carrier B to be depressed against the action of the spring 28. The ratchet wheel A, during the winding operation, will 45 slip under the locking ratchet wheel C but will be held by the latter against reverse or backward rotation. To release the brake, the brakeman pulls the release lever 38 in the direction indicated by the arrow *a* in 50 Fig. 2. The first result of this movement is to cause the bushing 36 to travel downwardly with respect to the locking ratchet wheel C, the threads 37 travelling down the threads 34. This action causes a depression 55 of the carrier B until the teeth 125 thereof are disengaged from the teeth 25 of the ratchet wheel A. Downward movement of the carrier B is limited by the carrier engaging the shoulder 40 of the bracket 14. 60 When the carrier B has been depressed to the limit of its movement, continued rotation of the bushing 36 will then cause the locking ratchet wheel C to be elevated within the socket 20 against the action of the 65 spring 35. In this connection it will be

understood that the depression of the carrier B is accomplished first because less resistance is afforded to its downward movement than to the upward movement of the ratchet wheel C because of the friction which will be present between the hub 33 and the enlargement 18, it being understood that said ratchet wheel C is under constant torque due to the constant tension exerted on the staff from the brake chain. From the preceding description, it will be seen that I eliminate the usual spring controlled pivoted dog; insure disengagement of the operating member before release of the staff can occur; and provide a much better holding arrangement than the usual single tooth locking dog which sometimes slips off of the ratchet tooth and allows the brake to release accidentally.

I have herein shown and described what I 85 now consider the preferred manner of carrying out the invention, but the same is merely illustrative and I contemplate all changes and modifications that come within the scope of the claims appended hereto.

I claim:

1. In a brake, the combination with a rotatable element having a ratchet wheel rotated in unison therewith, said ratchet wheel having two independent sets of ratchet teeth; of a manually operable oscillatable pawl member cooperable with one of said sets of ratchet teeth; a non-rotatable locking element cooperable with the other set of said ratchet teeth and normally yieldingly engaged therewith to prevent release movement of said rotatable element; and a manually operable release element oscillatable about the same axis as said rotatable element, said release and locking elements having cooperable engaging means effective to force the locking element away from and out of engagement with said ratchet wheel when said release element is oscillated about said axis.

2. In a brake, the combination with a rotatable element having a ratchet wheel rotated in unison therewith, said ratchet wheel having two independent sets of ratchet teeth; of a manually operable oscillatable pawl member cooperable with one of said sets of ratchet teeth; a non-rotatable locking element cooperable with the other set of said ratchet teeth and normally yieldingly engaged therewith to prevent release movement of said rotatable element; and an oscillatable manually operable release element, said release element and said locking element having cooperable steep pitch threads effective to disengage the locking element from said ratchet wheel when the release element is oscillated.

3. In a brake, the combination with a rotatable brake staff having a ratchet wheel rigid therewith, said ratchet wheel having

- two independent sets of ratchet teeth; of an oscillatable pawl member co-operable with one of said sets of teeth; spring means normally holding said member in operative engagement with said ratchet teeth, said member being movable axially of the staff against the action of said spring; a non-rotatable locking element cooperable with the other set of said ratchet teeth, said locking element being movable axially toward and from the ratchet teeth; spring means normally holding said locking element in operative engagement with said ratchet teeth; means directly engaging both the pawl and locking element for successively first disengaging said pawl member from its corresponding set of ratchet teeth and then the locking element from its corresponding set of ratchet teeth; and independent manually operated devices for effecting oscillation of said pawl and said disengaging means, respectively.
4. In a brake, the combination with a rotatable brake staff having a ratchet wheel rigid therewith, said ratchet wheel having two independent sets of ratchet teeth; of an oscillatable pawl member cooperable with one of said sets of teeth; spring means normally holding said member in operative engagement with one set of said ratchet teeth, said member being movable axially of the staff against the action of said spring; a non-rotatable locking element cooperable with the other set of said ratchet teeth, said locking element being movable axially toward and from the ratchet teeth; spring means normally holding said locking element in operative engagement with said ratchet teeth; and manually operable releasing means, oscillatable about the axis of said staff to successively first disengage said pawl member from its corresponding set of ratchet teeth and then the locking element from its corresponding set of ratchet teeth.
- 45 5. In a brake, the combination with a rotatable brake staff having a ratchet wheel rigid therewith, said ratchet wheel having two independent sets of ratchet teeth; spring means normally holding said member in operative engagement with one set of said ratchet teeth, said member being movable axially of the staff against the action of said spring; a non-rotatable locking element cooperable with the other set of said ratchet teeth, said locking element being movable axially toward and from the ratchet teeth; spring means normally holding said locking element in operative engagement with said ratchet teeth; and manually operable means for successively first disengaging said pawl member from its corresponding set of ratchet teeth and then the locking element from its corresponding set of ratchet teeth, said releasing means including an annular bushing surrounding the locking
- element, said locking element and bushing having cooperating steep pitch threads.
6. In a hand brake, the combination with a vertical brake staff having a ratchet wheel rotatable in unison therewith, said ratchet wheel having radially extending ratchet teeth on the top and bottom sides thereof; of an oscillatable pawl element cooperable with the ratchet teeth on one face of said ratchet wheel; a non-rotatable but axially movable ratchet wheel cooperable with the ratchet teeth on the other side of said ratchet wheel; and manually operable means bodily movable axially of said staff for successively first disengaging said pawl from said first named ratchet wheel and then said locking ratchet wheel from said first named ratchet wheel.
7. In a brake of the character described, the combination with a rotatable brake staff having a ratchet wheel rotatable in unison therewith, said ratchet wheel having radially extending ratchet teeth on the top and bottom sides thereof; of a pawl member oscillatable about the axis of said staff and cooperable with the ratchet teeth on the lower side of said ratchet wheel; a locking ratchet wheel cooperable with the ratchet teeth on the upper side of said ratchet wheel, said locking ratchet wheel having a hub of non-circular cross-section; a stationary bracket provided with a socket within which said hub is slidably mounted but prevented from rotation; spring means normally holding said locking ratchet wheel in operative engagement with said first named ratchet wheel; and manually operable means for successively first disengaging said pawl member from the first named ratchet wheel and then said locking ratchet wheel from the first named ratchet wheel, said disengaging means and locking ratchet being provided with co-acting sliding cam elements.
8. In a brake of the character described, the combination with a rotatable brake staff having a ratchet wheel rotatable in unison therewith, said ratchet wheel having radially extending ratchet teeth on the top and bottom sides thereof; of a pawl member oscillatable about the axis of said staff and cooperable with the ratchet teeth on the lower side of said ratchet wheel; a locking ratchet wheel cooperable with the ratchet teeth on the upper side of said ratchet wheel, said locking ratchet wheel having a hub of non-circular cross-section; a stationary bracket provided with a socket within which said hub is slidably mounted but prevented from rotation; spring means normally holding said locking ratchet wheel in operative engagement with said first named ratchet wheel; and manually operable means for successively first disengaging said pawl member from the first named ratchet wheel and then said locking ratchet wheel from the first named ratchet wheel, said disengaging means and locking ratchet being provided with co-acting sliding cam elements.

named ratchet wheel, said means comprising an annular bushing surrounding said locking ratchet wheel and having shouldered engagement with said pawl member, said bushing having interior steep pitch threads and said locking ratchet wheel having corresponding peripheral steep pitch threads.

9. In a hand brake, the combination with a vertical brake staff having a ratchet wheel 10 rotatable in unison therewith, said ratchet wheel having radially extending ratchet teeth on the top and bottom sides thereof; an axially movable oscillatable pawl element cooperable with the ratchet teeth on one face 15 of said ratchet wheel; a stop for limiting the axial movement of said pawl element;

a non-rotatable but axially movable ratchet wheel cooperable with the ratchet teeth on the other side of said ratchet wheel; and manually operated means for successively 20 first disengaging said pawl from said first named ratchet wheel and then said locking ratchet wheel from said first named ratchet wheel.

In witness that I claim the foregoing I 25 have hereunto subscribed my name this 30th day of Aug., 1921.

JOHN F. O'CONNOR.
